(57) **CLAIM**

The ornamental design for a nail polishing machine, as shown and described.

DESCRIPTION

FIG. 1 is a front view of a nail polishing machine showing my new design;

FIG. 2 is a front downwards perspective view of the main power and control system component of the nail polishing machine shown in isolation for clarity of illustration;

FIG. 3 is a rear downwards perspective view thereof;

FIG. 4 is a front upwards perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a right side downwards perspective view of the operative polishing component and stand of the nail polishing machine shown in isolation for clarity of illustration;

FIG. 12 is an upwards perspective view thereof;

FIG. 13 is a left side view thereof;

FIG. 14 is a right side view thereof;

FIG. 15 is a rear view thereof;

FIG. 16 is a front view thereof;

FIG. 17 is a top view thereof; and,

FIG. 18 is a bottom view thereof.

The broken line showing of dash-dash lines are included for the purpose of illustrating portions of the nail polishing machine and forms no part of the claimed design.

1 Claim, 13 Drawing Sheets
